DIRECTIONAL RADIO RECEIVER

Gordon S. Burroughs, Forest Hills, N. Y., assignor
to Federal Telephone and Radio Corporation,
New York, N. Y., a corporation of Delaware

Application January 8, 1946, Serial No. 639,845

6 Claims. (Cl. 343—121)

1

My invention relates to directional radio receivers, particularly to receivers for visually indicating the direction of received radio waves.

Directional radio receivers, such as so-called homing devices and radio compasses, usually have moving mechanical parts including motors, commutators, and revolving loop antennas. In addition to the mechanical disadvantages of such equipment, the electrical circuits are complicated, are not easily adjusted and do not produce an easily interpreted signal.

An object of my invention is a simplified directional radio receiver.

A further object of my invention is a directional radio receiver that is mechanically and electrically simple, and which produces an easily interpreted visual indication of direction.

My invention is defined in the appended claims and preferred embodiments are described in the following specification and shown in the accompanying drawing in which:

Fig. 1 is a diagrammatic showing of the circuits of one direction finder embodying my invention,

Fig. 2 shows the wave form of current in various parts of the circuits of Fig. 1, and

Fig. 3 is a diagrammatic showing of another embodiment of my novel direction finder.

The essential elements of my novel receiver are the loop 1, or other directional antenna having in combination with antenna 1, a cardioid field pattern, the cathode ray tube 2, the balanced modulating stage 3, the receiver 4 comprising the usual radio frequency amplifier and detector or demodulator, and the alternating current source 5. The loop may be fixedly mounted on the craft to be guided or may be manually rotated. The cathode ray screen shows a single radial line extending radially from near the center of the screen to its edge, much like the pointer of a meter. As the loop rotates, the line turns about the screen center, the angular position showing whether the transmitter, to which the receiver is tuned, is ahead or is to the right or left. The pointer moves from one side of center to the other as the loop rotates through the true bearing position.

Specifically, the terminals of the loop 1, balanced and grounded at its electrical center, are coupled in push-pull to the grid input circuits of the balanced modulator 3. The modulator is two side-by-side amplifier tubes such as triodes enclosed in a common or in separate envelopes, as desired. The anode or output circuits are connected in parallel to the input of the receiver and demodulator 4. Alternating current from the source 5 is applied in push-pull to the triode con-

2

trol grids. The source may be a commercial power transformer having a secondary winding 6 with a grounded center tap, and designed for and connected to a power source of commercial 60 cycle energy, or to the 400 cycle alternating current supply of an aeroplane.

A "sense" antenna 7 is coupled through appropriate 90° phase shifting means to the output of the modulator.

In operation, with the loop turned to one side a small angle from its null position, the low frequency modulating wave A from A. C. source 5, Fig. 2, combines with the radio frequency wave of the loop to produce wave B at the output. The sense antenna output C added to B results in wave D at the input to the receiver 4. The audio output of the receiver is then wave E, corresponding in frequency to the modulating wave from transformer 5. If, now, the loop is turned to a position on the other side of the null, the phase of the radio frequency voltage in the modulated wave B will be reversed 180 degrees so that when wave B is combined with the sense wave C, there is obtained wave F at the receiver input and wave G at the output. That is, when the loop is turned to the left, say, of the null, the receiver output is the same frequency and phase as the modulating voltage, and when the loop is turned to the right of the null, the receiver output is 180 degrees out of phase with the modulating voltage.

The amplitude of the receiver output varies in proportion to the amount the loop is turned away from the null. With the loop directly on the null, the demodulator output is zero. Hence, by comparing the phase of the demodulator output with the modulating voltage, the right-left bearing position of the loop may be indicated. One convenient means for making the comparison is a conventional cathode ray tube with magnetic or electrostatic deflection. Zero center voltmeters of various electrodynamometer or electrostatic types could be used for the same purpose. The cathode ray tube shown comprises the usual control and accelerating electrodes 8, 9 and 10, and beam deflecting coils 11 and 12 for moving the beam in two orthogonal directions over the fluorescent screen 13 of the tube.

One deflection coil, say the coil for horizontal deflection of the beam, is connected to the output of the demodulator, while the vertical deflection coil is connected to the modulating source, a separate secondary winding 14 on the transformer being used if desired.

When raw alternating current is applied to the voltage divider 15 for supplying the cathode

ray tube electrodes, the cyclic variations in potential affect all the electrodes in phase and thus do not disturb the proper voltage ratios for focusing the beam on the center of the screen. The spot however is extinguished during the negative half cycle and is illuminated during nearly all of the positive half cycle. With the A. C. voltage applied to the vertical deflection coil the beam tends to move vertically. The deflection sensitivity of the beam is being cyclically varied because of the cyclically varying potentials applied in the accelerating electrodes. The A. C. voltages applied in the deflection coils also vary cyclically in synchronism (being derived from the same source 5), with said potentials and tend to oppose them in their effect on the beam. However, the deflection of a magnetically deflected cathode ray tube is inversely proportional to the square root of the accelerating voltage and directly proportional to the deflecting voltage. Hence the forces do not balance and a radial line is traced during the positive half cycle.

By applying another alternating current voltage to the horizontal deflection coil in phase with the vertical deflection field, the line of light will incline to one side of the initial vertical position, and if the voltage applied to the horizontal coil is 180 degrees out of phase with the vertical deflection field, the line will incline to the other side the extent of inclination being determined by the amplitude. It is apparent now that if the output of the demodulator is applied to the horizontal coil and the modulating voltage is applied to the vertical coil the inclination of the line of light will instantaneously and accurately indicate the right-left direction of the loop antenna with respect to the direction of the received radio wave.

A clear, sharp line on the screen for accurate direction indication may be insured by a filter 16 connected in the output of the demodulator and designed to reject all frequencies except the single frequency of the modulating source. Herein lies an important feature of my invention. Since there are no commutators or slip rings with brushes, and no source of local electrical disturbances or spurious oscillations, it is only necessary for filter 16 to protect the deflection fields from received carrier modulations, noise, and the like. The effective filter may, in most systems of my invention, comprise simply a series resistor 17 and shunt condenser 18, as shown in Fig. 3.

The sensitivity of the cathode ray tube to changes in loop position may be materially increased by adjusting the audio output voltage applied to the vertical deflection coil to a value greater than the voltage applied to the horizontal deflection coil.

The voltages to be compared can with equal facility be applied to the deflection plates of a conventional electrostatic cathode ray tube, as suggested in Fig. 3 in the following manner. The control and accelerating electrodes 8, 9 and 10, should be energized with direct current, and may be tapped to the potentiometer 15 which is connected across a high voltage D. C. power supply 19. One pair of deflection plates 20 and 21 are connected across the output circuit of the demodulator, and the other pair of deflection plates 22 and 23 are connected across the alternating modulating source. The deflecting voltages for the two pairs of plates are developed, respectively, across the high ohmic resistors 24 and 25 which are each connected at one end to the positive side of the high voltage potentiometer 15 so that

the alternating deflection voltage moves the beam equal distances either side of center. The voltages are preferably adjusted to extend the line of light from edge-to-edge of the screen. As before the line pivots about the screen center in response to rotation of the loop antenna either side of null.

My improved directional radio receiver is mechanically and electrically simple, is easy to adjust, and produces an easily interpreted visual indication of direction.

I claim:

1. A radio direction finder comprising, a directional antenna; a cathode ray tube having a fluorescent screen, a cooperating electron beam source, control electrodes for said electron beam and magnetic electron beam deflection elements; an alternating current source, means for modulating the radio frequency waves appearing at the terminals of said antenna with the waves of different phase from said source, a demodulator connected to the modulating means for deriving the modulated wave, connections between the electron beam deflection elements, respectively, and the output of said demodulator and said alternating current source and means for energizing said control electrodes with waves from said alternating current source.

2. In a radio direction finder, a modulator, said modulator comprising two electron discharge devices each having a cathode, a control grid, and an anode; a directional receiving antenna balanced with respect to ground so that the phases of the radio frequency voltages appearing at the terminals of the antenna are opposed, couplings between said terminals, respectively, and said control grids, a source of modulating voltage connected in push-pull to said grids, a non-directional antenna, a demodulator, the input of said demodulator being connected to said non-directional antenna and to said anodes, a cathode ray tube comprising an electron beam source, control electrodes for said electron beam, two orthogonal magnetic beam deflecting means, said deflecting means being connected, respectively, to the output of said demodulator and to said source of modulating voltage and means for energizing said control electrodes with waves from said alternating current source.

3. A direction finder comprising an antenna loop, the electrical center of the loop being grounded, two amplifiers, an alternating voltage source, a transformer winding with a grounded center tap, means for energizing said winding with energy from said alternating voltage source one terminal of said loop and one terminal of said winding being coupled together and connected to the input circuit of one of said amplifiers, the remaining terminals of said loop and said transformer being coupled together and to the input circuit of the other amplifier, a sense antenna, a demodulator, the output circuits of said amplifiers and said sense antenna being connected together and to the input circuit of said demodulator, and a cathode ray oscilloscope for comparing the phase of the output of said demodulator with the phase of the voltage across said transformer winding comprising an electron beam source, control electrodes for said electron beam, two sets of magnetic deflection elements means for applying the output of said demodulator to one set of deflection elements, means for applying energy from said alternating voltage source to another set of deflection elements and

means for applying energy from said alternating voltage source to said control electrodes.

4. A direction finder according to claim 3 comprising a filter for selectively passing the modulations of said modulator, connected between said demodulator and said cathode ray oscilloscope.

5. A right-left radio direction finding system comprising a directive antenna system, a source of alternating voltage, means for modulating the output of said directive antenna system in push-pull with said alternating voltage to produce an effective angular sweeping of the directive pattern of said directive antenna system, means for demodulating the output of said antenna system, 15 a cathode ray oscilloscope comprising an electron beam source, control electrodes for said electron beam, and sets of magnetic deflection elements, means for applying said demodulated antenna system output to one set of deflection elements, means for applying said alternating voltage to another set of deflection elements and means for applying said alternating voltage to said control electrodes.

6. An arrangement according to claim 5, further comprising an omni-directional antenna and means for combining the output of said omni-directional antenna with said modulated antenna output before demodulation.
